CLAIM

The ornamental design for an intracavitory ultrasonic probe, as shown and described.

DESCRIPTION

FIG. 1 is a perspective view of an intracavitory ultrasonic probe;

FIG. 2 is a front view of the intracavitory ultrasonic probe;

FIG. 3 is a rear view of the intracavitory ultrasonic probe;

FIG. 4 is a left side view of the intracavitory ultrasonic probe;

FIG. 5 is a right side view of the intracavitory ultrasonic probe;

FIG. 6 is a top view of the intracavitory ultrasonic probe;

FIG. 7 is a bottom view of the intracavitory ultrasonic probe;

FIG. 8 is a partially enlarged view of part 1 as shown in FIG. 1;

FIG. 9 is a partially enlarged view of part 2 as shown in FIG. 1;

FIG. 10 is a partially enlarged view of part 3 as shown in FIG. 1;

FIG. 11 is a partially enlarged view of part 4 as shown in FIG. 4;

FIG. 12 is a partially enlarged view of part 5 as shown in FIG. 4;

FIG. 13 is a partially enlarged view of part 6 as shown in FIG. 5;

FIG. 14 is a partially enlarged view of part 7 as shown in FIG. 5;

FIG. 15 is a partially enlarged view of part 8 as shown in FIG. 6; and,

FIG. 16 is a partially enlarged view of part 9 as shown in FIG. 7.
